CURRENT COLLECTOR HEAD FOR TROLLEY ELECTRIFICATION SYSTEM

James A. Corl, San Carlos, Calif., assignor to Insul-8
Corp., San Carlos, Calif., a corporation of California

Filed July 2, 1963, Ser. No. 75,639

Term of patent 14 years

(Cl. D41—1)

Fig. 1.

Fig. 2.

Fig. 3.

FIG. 1 is a perspective view of a current collector head for trolley electrification system in accordance with my invention;

FIG. 2 is a typical side elevational view of the current collector head shown in FIG. 1, opposite sides of which are identical; and,

FIG. 3 is a typical end elevational view of the current collector head shown in FIG. 1, opposite ends of which are identical.

I claim:

The ornamental design for current collector head for trolley electrification system, as shown and described.
